AUTOMATIC ADJUSTABLE CHAIR

Harold Gleitsman, New Rochelle, and Daniel Hoenig, St. Albans, N. Y.; said Hoenig assignor to said Gleitsman

Application August 17, 1945, Serial No. 611,048

16 Claims. (Cl. 155—119)

1

This invention relates to automatically adjustable chairs.

The primary object of this invention is to provide a chair having a back which is automatically adjustable to different positions in response to different postures assumed thereon by the user of the chair.

In its more specific aspects, it is an object of the present invention to provide a chair which is convertible automatically from a chair on which a person may be comfortably seated in a more or less upright position to a chair on which the user may be comfortably supported in a reclining position. An important feature of the chair of the present invention is that the operation of adjusting or converting the chair is accomplished without manual manipulations, but is effected, as stated, automatically, in response to the positions on the chair of the user thereof.

Another object of the present invention is to provide a chair of the character described above which is of simple construction and which can be produced at low cost.

A further object is the provision of an automatically adjustable chair which can be folded into compact form for convenience in carrying or shipping.

A yet further object is generally to provide an improved automatically adjustable chair.

The above and other objects, features and advantages of the present invention will be fully understood from the following description, reference being had to the accompanying drawings which are to be considered as illustrative of the invention, but not in limitation thereof.

In the drawings:

Fig. 1 is a perspective view of a chair embodying the present invention, the back of the chair being in the position in which the chair is a reclining chair;

Fig. 1A is a side view of the chair in the folded condition thereof;

Fig. 2 is a sectional view on the line 2—2 of Fig. 1;

Fig. 3 is a view similar to Fig. 2 showing the position of the back of the chair as a back rest for the user when the latter is seated on the chair in a more or less upright position;

Fig. 4 is a sectional view on the line 4—4 of Fig. 3;

Fig. 5 is a fragmentary perspective view of one of the sides of the seat frame of the chair;

Fig. 6 is a view similar to Fig. 1 showing another form of the invention;

2

Fig. 7 is a sectional view on the line 7—7 of Fig. 6;

Fig. 8 is a view similar to Fig. 7 showing the back of the chair adjusted to the position for providing a back rest when the user is seated on the chair in a more or less upright position;

Fig. 9 is a perspective view of the upper, rear end portion of the seat frame;

Fig. 10 is a view similar to Fig. 9 showing a modification.

Referring now to the drawings in detail and first to the form of the invention illustrated in Figs. 1 to 5, the chair 10 of the present invention comprises a seat frame 12 and a back frame 14 which is movably mounted on said seat frame. As here shown, frames 12 and 14 are formed of wood but, of course, can be formed of any other suitable material. The seat frame 12 comprises the side members 16, illustrated as flat planar members, connected at the forward ends thereof by the upper and lower cross members 18 and 20, respectively, and connected at the rear ends thereof by the cross member 22. The back frame comprises side members 24 and an upper cross member 26 and a lower cross member 28.

Cross member 22 of seat frame 12 constitutes fulcrum means for the lower end portions of side members 24 of the back frame 14, said lower end portions of members 24 being in pivotal engagement with said fulcrum means for forward and backward pivotal movement of the back frame about a horizontal axis. It is apparent, however, that the fulcrum means may be other than a cross member of the frame. Interengaging guide means are provided on the two frames in position above the fulcrum means constituted by cross member 22, for mounting the back frame 14 for pivotal movement and for guiding and limiting the pivotal movement of the back frame about the axis of said fulcrum means. The interengaging means just referred to, are preferably constituted by pins and grooves, specifically the grooves 30 provided in the side members 16 of the seat frame 12 and the companion lateral pin projections 32 of the lower cross member 28 of the back frame.

As here shown, the seat 34 of the chair is formed of canvas or other suitable sheet material and is secured to the upper cross member 18 at the forward part of the seat frame 12 and to the lower cross member 28 of the back frame 14. Thus, the seat 34 also constitutes means for connecting the lower part of the back frame to the forward upper part of the seat frame. It will be understood, however, that this connecting means may be in various other forms and

need not, in itself, constitute the seat of the chair. The back frame 14 is provided with a back rest 36 which, as here shown, is formed of canvas, but which may be formed of any other suitable material, the lower end of back 36 being secured to lower cross member 28 and the upper end of said back being secured to upper cross member 26. It will be noted that the rear end portion of the seat or connecting means 34 is looped around cross member 28, as indicated at 38, of the frame 14 and is stitched to the lower end of the back rest 36, as indicated at 40. The back frame 14 is provided with a cross band 42 of fabric or other suitable material for supporting the back rest 36 between the upper and lower cross members 26 and 28 when the user of the chair leans against the back of the chair. It will be understood, however, that said band 42 may be omitted and also that the back rest 36 may be formed in various other ways.

When the user of the chair is seated thereon in a more or less upright position, the weight of the user on the seat or connecting means 34 is transmitted to the back frame 14 whereby to exert a force thereon which pivotally moves the back frame forwardly about the axis of the fulcrum means until the lateral projections or pins 32 engage the forward ends 42 of the companion grooves 30, respectively, of the side members 16 of the seat frame 12. In this position of connecting means 34, the latter, when formed of fabric or the like, is bowed downwardly along a curved line extending between cross members 18 and 28. On the other hand, when the user of the chair is seated thereon in an upright position and wishes to assume a reclining position on the chair, back frame 14 is automatically moved pivotally backward about the axis of the fulcrum means constituted by cross member 22 in response to the pressure exerted by the user on the back of the chair in assuming a reclining posture thereon. This backward movement of the back frame 14 is facilitated by the natural shifting of the user's body forwardly of the seat 34 while pressing against the back rest 36 of the frame 14, this forward shifting movement of the user's body resulting in easing of the force which opposes the backward movement of the back frame 14 by the pressure of the user's back thereon. However, it will be understood that so long as the user purposely exerts a greater force on the back of the chair for tilting the same backwardly than is exerted by the user on the seat or connecting means 34 for holding the lateral extensions or pins 32 in their positions at the forward ends of the companion grooves 30, which occurs when the user wishes to change from a sitting position to a reclining position on the chair, the back of the chair is automatically moved backwardly to a position in which it provides a back rest for the user in the latter's reclining position.

The operation of the chair can be more clearly understood from the fact that when the chair is unoccupied and the back thereof is in its forward position the seat or connecting means 34 is slack, while, on the other hand, when the back frame is in its rear position, the seat or connecting means 34 is less slack or may be taut. Thus, the connecting means 34 has a limited front to rear planar extensibility and contractability whereby the back of the chair is movable from a forward position to a backward position in response to pressure of the user's back thereon when the user correspondingly alters his or her

position while supported on the chair and whereby said connecting means is operable by the weight of the user to move the back of the chair forwardly, in engagement with fulcrum means 22, from a backward position when the user's position on the chair is correspondingly altered. It will be understood however that this planar extensibility and contractability for accomplishing these results may be provided, within the scope of this invention, by various means other than a sheet of fabric and in various other ways.

If desired, the grooves 42 may be so designed that the rear ends 44 thereof are located so that they are engaged by the lateral projections 32 when the back frame is in its rearmost position, but as shown, this is not essential since the backward movement of the back frame 14 can be limited by the tension of the connecting means or seat 34 on cross member 28. It will be observed that the lower end portions of the side members 24 which pivotally engage the cross member or fulcrum means 22 also have a sliding engagement with said cross member, transversely thereof, since the back frame 14 moves upwardly while it is being moved rearwardly. In this connection, it will be observed that the intermediate portion 46 of the lower edge of each groove 42 is curved upwardly from the forward edge portion 48 of said groove for the purpose of providing a degree of resistance to releasably oppose the backward movement of the back frame 14 from its forward position, whereby the user of the chair is required to exert the proper amount of pressure thereon, in order to move the back frame rearwardly when the user wishes to assume a reclining position on the chair. It will be understood that the need for the user thus to consciously and purposefully press upon the back of the chair, when he wishes to assume a reclining position thereon, prevents inadvertent backward movement of the back frame 14 when the user intends to remain in a sitting position with his back resting against the back of the chair. It will be noted that the upper edge portion of groove 30 is recessed, as indicated at 50, to provide clearance for, and avoid binding of, the companion lateral extension 32 in the forward end of said groove when the user leans against the back frame 14 in its forward position in order to tilt the same backwards.

It will be observed that, as shown in Fig. 1A, the chair 10 is foldable, for convenience in carrying or shipping, this being permitted by the releasable engagement of the side members 24 of the back frame with the cross member or fulcrum means 22 and by the pivotal engagement of the lateral extensions or pins 32 of the back frame with the side member 16 of the seat frame in the companion grooves 30 thereof. In this connection, it will be understood that pins 32 are preferably of circular peripheral contour to facilitate the pivotal movement of said pins in the companion grooves. As here shown, the lower parts of the side members 16 of the seat frame are provided with cut-outs or hand-openings 52 to facilitate the carrying of the chair when the latter is in its folded condition.

Referring now to the form of the invention illustrated in Figs. 6 to 9, it will be observed that the chair 10A embodies the same underlying idea and principles of the invention applied in the form of the chair 10 illustrated in Figs. 1 to 5 and hereinbefore described. In this form of the invention, however, the seat frame 12A and the back frame 14A are formed of metal, preferably tubular metal stock, and the cross member 22A

which corresponds to the cross member 22 and which, like the latter, provides fulcrum means for the lower end portions of the side members of the back frame 14A, is integral with the sides 16A of the seat frame 12A. The cross member 18A which corresponds to the cross member 18 of chair 10 may be secured between the side frame members 16A in any suitable way, as by being welded thereto or by projecting the end portions of the cross member 18A in companion openings in the adjacent side members 16A with upsetting or riveting of said end portions to fasten said cross member in position. The lower cross member 28A which corresponds to the lower cross member 28 of chair 10 is similarly provided with lateral extensions or pins 32A which engage the side members of the seat frame 12A in grooves 30A which correspond to the grooves 30 of the side members of chair 10. As here shown, groove 30A is formed in a metal member 54 which is secured in position to the upper rear end portions 56 of the side member 16A of the seat frame in any suitable way, as by being welded or riveted to the companion end portions 56, the latter being flattened to facilitate the securing of members 54 thereto. However, as illustrated in Fig. 10, the separate members 54 may be omitted and the grooves 30A may be formed directly in the flattened end portions 56. The connecting means 34A is the same as the connecting means 34 of chair 10 and likewise the back 36A and the cross band 42A are the same as the back 36 and cross band 42, respectively, of chair 10. It will be understood that chair 10A operates in the same way as chair 10 as described above.

It is apparent that chairs of the present invention may be used for various purposes. For example, said chairs may be used as beach chairs, lawn chairs, porch chairs, etc., and also as chairs suitable for use within a house or other building. It will be noted that the chair 10 is illustrated as of the low-seat type, while the seat of chair 10A is at a higher level, but it will be understood that the height of the seats of either of these chairs can be different from that illustrated. Also it is apparent that the connecting means 34 by which the user is able to effect the adjustment of the back frame of the chair merely by changing his position in the chair, can be formed in numerous other ways different from that shown and likewise it will be understood that said connecting means need not necessarily constitute the seat of the chair but that the seat of the chair can be constituted by any suitable seat supported by the connecting means without, however, interfering with the front-to-rear extensible and contractile characteristic of the connecting means as described above.

Finally, it will be understood that various other changes in the details of construction and in the arrangement of parts may be made without departing from the underlying idea or principles of the present invention within the scope of the appended claims.

Further it will be understood that, as used in the claims, the term chair includes within its scope and meaning not only a chair proper, but also other furniture, for example, a chaise lounge, a couch, etc., having a part which may be used as a back rest either in a more or less upright position or in a position for supporting the user in a reclining position.

Having thus described our invention, what we claim and desire to secure by Letters Patent is:

ing a seat frame having spaced connected side members, a movable back frame between said side members, fulcrum means on said seat frame engageable by the lower part of said back frame for the backward and forward pivotal movement of the latter about a horizontal axis, interengaging means on said two frames for mounting said back frame for said pivotal movement thereof, and means operatively connected to said seat-frame and said back frame and operable by the weight of the user of the chair for moving said back frame from a backward position pivotally to a forward position.

2. An automatically adjustable chair comprising a seat frame having spaced connected side members, a movable back frame between said side members, fulcrum means on said seat frame engageable by the lower part of said back frame for the backward and forward pivotal movement of the latter about a horizontal axis, interengaging means on said two frames for mounting said back frame for said pivotal movement thereof, and means operatively connected to said seat-frame and said back frame and operable by the weight of the user of the chair for moving said back frame from a backward position pivotally to a forward position, said connecting means having a limited front to rear planar extensibility whereby said back frame is movable from a forward position to a backward position in response to pressure of the user's back thereon when the user correspondingly alters his position while supported on the chair.

3. An automatically adjustable chair comprising a seat frame having spaced connected side members, a movable back frame between said side members, fulcrum means on said seat frame engageable by the lower part of said back frame for the backward and forward pivotal movement of the latter about a horizontal axis, interengaging means on said two frames for mounting said back frame for said pivotal movement thereof, and connecting means secured to said seat frame and operatively connected to said back frame above said fulcrum and having a limited front to rear planar extensibility whereby said back frame is movable backwardly, while engaged with said fulcrum means, from a forward position to a backward position in response to pressure of the user's back thereon when the user correspondingly alters his position while supported on the chair, said connecting means being operable by the weight of the user thereon to move the back frame forwardly, while engaged with said fulcrum means, from a backward position when the user correspondingly alters his position while supported on the chair.

4. An automatically adjustable chair comprising a seat frame having spaced connected side members, a movable back frame between said side members, means connecting the lower part of said back frame to the forward part of said seat frame and providing means to support the user of the chair in sitting and reclining postures thereon, fulcrum means on said seat frame located below the point of attachment of said connecting means to said back frame and pivotally engaged by said back frame, and interengaging means on said two frames for mounting said back frame for pivotal movement about a horizontal axis and for guiding the pivotal movement of said back frame about said axis.

5. An automatically adjustable chair comprising a seat frame having spaced connected side members, a movable back frame between said side

7. members, means connecting the lower part of said back frame to the forward part of said seat frame and providing means to support the user of the chair in sitting and reclining postures thereon, fulcrum means on said seat frame located below the point of attachment of said connecting means to said back frame and pivotally engaged by said back frame, and interengaging means on said two frames for mounting said back frame for pivotal movement about a horizontal axis and for guiding the pivotal movement of said back frame about said axis, said connecting means being movable with the back frame when the user presses against the latter to move the same rearwardly, said connecting means being also operable to transmit the force of the user's weight thereon to the back frame, for moving the same forwardly from a backward position thereof.

6. An automatically adjustable chair comprising a seat frame having spaced connected side members, a movable back frame between said side members, fulcrum means on said seat frame engageable by the lower part of said back frame for the backward and forward pivotal movement of the latter about a horizontal axis, interengaging means on said two frames for mounting said back frame for said pivotal movement thereof, and means operatively connected to said seat frame and said back frame and operable by the weight of the user of the chair for moving said back frame from a backward position pivotally to a forward position, said connecting means forming the seat of the chair and having a limited front to rear planar extensibility whereby said back frame is movable from a forward position to a backward position in response to pressure of the user's back thereon when the user correspondingly alters his position while supported on the chair.

7. An automatically adjustable chair comprising a seat frame having spaced connected side members, a movable back frame between said side members, fulcrum means on said seat frame engageable by the lower part of said back frame for the backward and forward pivotal movement of the latter about a horizontal axis, interengaging means on said two frames for mounting said back frame for said pivotal movement thereof, and means operatively connected to said seat frame and said back frame and operable by the weight of the user of the chair for moving said back frame from a backward position pivotally to a forward position, said connecting means forming the seat of the chair and having a limited front to rear planar extensibility whereby said back frame is movable from a forward position to a backward position in response to pressure of the user's back thereon when the user correspondingly alters his position while supported on the chair, said connecting means being operable by the weight of the user thereon to move the back frame forwardly, while engaged with said fulcrum means, from a backward position when the user correspondingly alters his position while supported on the chair.

8. An automatically adjustable chair comprising a seat frame having spaced connected side members, a movable back frame between said side members, fulcrum means on said seat frame engageable by the lower part of said back frame for the backward and forward pivotal movement of the latter about a horizontal axis, interengaging means comprising guide-grooves and companion pins, respectively, on said two frames for mounting said back frame for said pivotal move-

ment thereof, said interengaging means being located above said fulcrum means, and connecting means secured to said seat frame and operatively connected to said back frame above said fulcrum and having a limited front to rear planar extensibility whereby said back frame is movable backwardly, while engaged with said fulcrum means, from a forward position to a backward position in response to pressure of the user's back thereon when the user correspondingly alters his position while supported on the chair, said connecting means being operable by the weight of the user thereon to move the back frame forwardly, while engaged with said fulcrum means, from a backward position when the user correspondingly alters his position while supported on the chair.

9. An automatically adjustable chair comprising a seat frame having spaced connected side members, a movable back frame having spaced connected side elements and extending between said side members, fulcrum means on said seat frame engageable by the lower part of said back frame for the backward and forward pivotal movement of the latter about a horizontal axis, interengaging means on said two frames for mounting said back frame for said pivotal movement thereof, and means formed of flexible sheet material forming a seat for the chair and extending between said side elements at the lower part of the back frame, above said fulcrum means, and between said side members at the forward part of said seat frame and fixedly secured to said two frames at said parts, respectively, thereof, said last mentioned means being operable by the weight of the user of the chair for moving said back frame from a backward position pivotally to a forward position and having a limited front to rear planar extensibility whereby said back frame is movable from a forward position to a backward position in response to pressure of the user's back thereon when the user correspondingly alters his position while supported on the chair.

10. An automatically adjustable chair comprising a seat frame having spaced connected side members, a movable back frame having spaced connected side elements and extending between said side members, fulcrum means on said seat frame engageable by the lower part of said back frame for the backward and forward pivotal movement of the latter about a horizontal axis, interengaging means comprising guide-grooves and companion pins, respectively, on said two frames for mounting said back frame for pivotal movement thereof, said interengaging means being located above said fulcrum means, and means formed of flexible sheet material forming a seat for the chair and extending between said side elements at the lower part of the back frame, above said fulcrum means, and between said side members at the forward part of said seat frame and fixedly secured to said two frames at said parts, respectively, thereof, said last mentioned means being operable by the weight of the user of the chair for moving said back frame from a backward position pivotally to a forward position and having a limited front to rear planar extensibility whereby said back frame is movable from a forward position to a backward position in response to pressure of the user's back thereon when the user correspondingly alters his position while supported on the chair.

11. An automatically adjustable chair comprising a seat frame provided with laterally spaced sides having longitudinal grooves in their rear portions, a pivotally movable back frame having

lateral projections pivotally engaging said sides in said grooves and movable therein longitudinally thereof, a cross member at the rear part of said seat frame below the level of said grooves, said back frame being pivotally engageable with said cross member and slidably transversely thereof, said seat frame having a cross member at the forward part thereof, and means having a limited extensibility in a front to rear plane connecting said last mentioned cross member to said back frame at a point on the latter above said first mentioned cross member.

12. An automatically adjustable chair comprising a seat frame provided with laterally spaced sides having longitudinal grooves in their rear portions, a pivotally movable back frame having lateral projections pivotally engaging said sides in said grooves and movable therein longitudinally thereof, a cross member at the rear part of said seat frame below the level of said grooves, said back frame being pivotally engageable with said cross member and slidably transversely thereof, said seat frame having a cross member at the forward part thereof, and means having a limited extensibility in a front to rear plane connecting said last mentioned cross member to said back frame at a point on the latter above said first mentioned cross member, said grooves having forward edge portions engaged by said lateral projections and contoured to provide releasable resistance to the movement of said projections longitudinally of said grooves toward the rear ends thereof, whereby pressure applied to said back frame for moving the same backwardly causes the latter to pivot on said first mentioned cross rod and to slide transversely thereof in an upward direction.

13. An automatically adjustable chair comprising a seat frame provided with laterally spaced sides having longitudinal grooves in their rear portions, a pivotally movable back frame having lateral projections pivotally engaging said sides in said grooves and movable therein longitudinally thereof, a cross member at the rear part of said seat frame below the level of said grooves, said back frame being pivotally engageable with said cross member and slidably transversely thereof, said seat frame having a cross member at the forward part thereof, and means having a limited extensibility in a front to rear plane connecting said last mentioned cross member to said back frame at a point on the latter above said first mentioned cross member, said grooves having forward edge portions engaged by said lateral projections and contoured to provide releasable resistance to the movement of said projections longitudinally of said grooves toward the rear ends thereof, whereby pressure applied to said back frame for moving the same backwardly causes the latter to pivot on said first mentioned cross rod and to slide transversely thereof in an upward direction, said back frame being disengagable from said first mentioned cross member and pivotally movable to a forward position in folded relation to said seat frame.

14. An automatically adjustable chair comprising a seat frame provided with laterally spaced sides having longitudinal grooves in their rear portions, a pivotally movable back frame having lateral projections pivotally engaging said sides

in said grooves and movable therein longitudinally thereof, a cross member at the rear part of said seat frame below the level of said grooves, said back frame being pivotally engageable with said cross member and slidably transversely thereof, said seat frame having a cross member at the forward part thereof, and means having a limited extensibility in a front to rear plane connecting said last mentioned cross member to said back frame at a point on the latter above said first mentioned cross member, said seat frame being formed of metal and said first mentioned cross rod being integral with the sides of said seat frame.

15. An automatically adjustable chair comprising a seat frame provided with laterally spaced sides having longitudinal grooves in their rear portions, a pivotally movable back frame having lateral projections pivotally engaging said sides in said grooves and movable therein longitudinally thereof, a cross member at the rear part of said seat frame below the level of said grooves, said back frame being pivotally engageable with said cross member and slidably transversely thereof, said seat frame having a cross member at the forward part thereof, and means having a limited extensibility in a front to rear plane connecting said last mentioned cross member to said back frame at a point on the latter above said first mentioned cross member, said sides of the seat frame being formed of flat planar members.

16. An automatically adjustable chair comprising a seat frame having laterally spaced parts provided with horizontal grooves therein at the rear portions thereof, said grooves extending longitudinally of said parts, respectively, and having convexly curved lower edges, a back frame having portions at a lower part thereof slidably and pivotally engaging said parts of the seat frame in said grooves on said edges, means anchored at the front thereof to the forward part of said seat frame, extending rearwardly from said forward part and connected to a lower part of said back frame and movable therewith in the sliding and pivotal movements thereof on said seat frame, and fulcrum means on said seat frame on which said back frame has a pivotal engagement below said connecting means, said back frame being movable toward the forward ends of said grooves by the force of the weight of the user of the chair applied downwardly on said connecting means when seated on the chair, the rear movement of said back frame being releasably opposed by said convexly curved edges of said grooves.
